(57) **CLAIM**

The ornamental design for an socket tool, as shown and described.

DESCRIPTION

FIG. 1 is a perspective view of a socket tool showing my new design according to a first embodiment;

FIG. 2 is a front view thereof;

FIG. 3 is a rear view thereof;

FIG. 4 is a left side view thereof;

FIG. 5 is a right side view thereof;

FIG. 6 is a bottom plan view thereof;

FIG. 7 is a top plan view thereof;

FIG. 8 is a perspective view in a use state;

FIG. 9 is a perspective view in another use state;

FIG. 10 is a perspective view of a socket tool showing my new design according to a second embodiment;

FIG. 11 is a front view thereof;

FIG. 12 is a rear view thereof;

FIG. 13 is a left side view thereof;

FIG. 14 is a right side view thereof;

FIG. 15 is a bottom plan view thereof;

FIG. 16 is a top plan view thereof;

FIG. 17 is a perspective view in a use state; and,

FIG. 18 is a perspective view in another use state.

The broken lines shown in the drawings depict portions of the socket tool in which the design is embodied, that form no part of the claimed design.
